(57) **CLAIM**

The ornamental design for a vehicle wheel as shown and described.

DESCRIPTION

FIG. 1 is a front perspective view of a vehicle wheel illustrating an embodiment of our new design;

FIG. 2 is a rear perspective view thereof;

FIG. 3 is a front view thereof;

FIG. 4 is a rear view thereof; and,

FIG. 5 is a side view thereof.

The broken lines in the drawings are included for the purpose of illustrating environmental structure and form no part of the claimed design. The dot-dashed lines are included for the purpose of illustrating boundary lines and form no part of the claimed design. The side view depicted in FIGS. 5 depicts a view of the vehicle wheel from a single side (e.g., a left side view or a right side view) and it should be understood that each of these side views are the same.
